[57] CLAIM

The ornamental design for a reset button extender for computers or the like, as shown.

DESCRIPTION

FIG. 1 is a front elevational view of a reset button extender for computers or the like showing my new design;

FIG. 2 is a rear elevational view;

FIG. 3 is a side elevational view taken from the right of FIG. 1, the side opposite being a mirror image thereof;

FIG. 4 is a top plan view; and

FIG. 5 is a bottom plan view.

FIG. 1

FIG. 2

FIG. 3

FIG. 4

FIG. 5
